UNITED STATES PATENT OFFICE.

ALFRED G. KINTZ, OF WALLINGFORD, CONNECTICUT, ASSIGNOR TO INTERNATIONAL SILVER CO., OF MERIDEN, CONNECTICUT, A CORPORATION OF NEW JERSEY.

DESIGN FOR A DISH, PLATE, OR SIMILAR ARTICLE.

51,459.

Specification for Design.

Patented Nov. 6, 1917.

Application filed August 24, 1917. Serial No. 188,078. Term of patent 3½ years.

To all whom it may concern:

Be it known that I, ALFRED G. KINTZ, a citizen of the United States, residing at Wallingford, in the county of New Haven and State of Connecticut, have invented a new, original, and ornamental Design for a Dish, Plate, or Similar Article, of which the following is a specification, reference being had to the accompanying drawing, forming part thereof.

Figure 1 is a plan view of a dish, plate or similar article, showing my new design.

Fig. 2 is a side view.

I claim:—

The ornamental design for a dish, plate, or similar article, as shown.

ALFRED G. KINTZ.

Witnesses:

GENEVIEVE ROCHE,
NELSON STILES.
